UNITED STATES PATENT OFFICE.

WILLIAM H. BLAKE, OF WATERBURY, CONNECTICUT, ASSIGNOR TO NOVELTY MANUFACTURING COMPANY, OF SAME PLACE.

DESIGN FOR AN UMBRELLA TIP-CUP.

Specification forming part of Design No. **11,332**, dated August 12, 1879; application filed July 14, 1879.
[Term of patent 7 years.]

To all whom it may concern:

Be it known that I, WILLIAM H. BLAKE, of Waterbury, in the State of Connecticut, have invented a new and useful Design for Tip-Cups, of which the following is a specification.

Tip-cups for umbrellas and parasols have been made of a variety of ornamental shapes, such as cylindrical, curved, and hexagonal.

The ornamental form that I have designed is represented in accompanying drawings by the elevation, Figure 1, and plan, Fig. 2.

The tip-cup is of a circular form, the portion *a* being cylindrical. The part *b* above the cylindrical part *a* is a concave bevel, extending backwardly to the top part, *d*, of the tip-cup, which is flat, or nearly so.

The edge of the tip-cup is contracted, and there is a concave bevel, *c*, between the same and the cylinder *a*.

This design is ornamental, and the cylinder *a* stands out boldly from the concave bevels at each side, and produces a pleasing æsthetic effect.

The surfaces of the metal tip-cup may be polished, frosted, or otherwise ornamented.

I claim as my invention—

The design for an umbrella tip-cup, consisting of the cylindrical portion *a*, concave beveled portions *b* *c*, and top portion, *d*, as described, and shown in the accompanying illustration.

Signed by me this 5th day of July, A. D. 1879.

WILLIAM H. BLAKE.
